assignor to International Standard Electric
Corporation, New York, N. Y., a corporation of
Delaware

Application January 9, 1940, Serial No. 313,035

19 Claims. (Cl. 179—171.5)

The present invention relates to systems for delivering modulated carrier waves, and especially to such systems wherein the wave is delivered by a vacuum tube whose grid is energized, preferably with modulating signal and unmodulated carrier, from two driver sources of poor regulation, the biases on such vacuum tube being so related to the amplitude of excitation of the grid that grid current is drawn periodically during intervals corresponding to maximum amplitude of the output wave.

It is an object of the present invention to provide such a system wherein the distortions which tend to result from the drawing of grid current are prevented or considerably minimized.

It is another object of my invention to provide such a system wherein the driver source is not required to give as much power nor to have as good a voltage regulation as is the case in previously known systems.

The invention is particularly applicable to a modulation arrangement wherein the modulating tube is separately fed with unmodulated carrier frequency and audio frequency energy from separate driving sources at least one of which has inherently a comparatively poor voltage regulation. In such systems ordinarily for the sake of obtaining reasonably high outputs from the modulating tube the grid of this tube is so biased that it becomes conductive during the positive peaks of the impressed audio voltage, and this conductivity of the grid, together with the poor regulation of the carrier and/or audio driver, distorts the voltage delivered by such carrier and/or audio driver, thus giving a corresponding distortion in the envelope of the modulated output wave. In known systems of this type such distortion has been avoided only by designing the carrier and audio driver sources so as to have inherently good voltage regulation—an inherently expensive requirement—or by designing these driver sources to deliver much more power than is actually required even in the intervals of maximum grid current, and then dissipating the greater part of this power in a swamping resistor so that the effective load on these driver sources will not vary greatly when the grid of the modulated tube becomes conductive.

In accordance with the present invention it is proposed to design the carrier and audio sources in an economical manner so that these have only sufficient power to supply the requirements of the modulating tube grid when the latter becomes conductive at the peaks of the audio cycle.

Then absorption means are provided for normally absorbing a part of this power when the grid is non-conductive, these absorption means being varied automatically in response to the flow of the grid current itself, so as to decrease the absorption thereof at those moments when the grid itself is conductive and thus requires the whole power output of the drivers.

The invention may be best understood by reference to the attached drawing in which:

Figs. 1 and 2 represent two embodiments of the invention respectively employing series and parallel connections of the driver sources;

Figs. 3, 4 and 5 represent circuit modifications which may be made in the circuits of Figs. 1 and 2 in accordance with alternative forms of my invention;

Figs. 6, 7, 8 and 9 represent still further circuit modifications which may be made in the circuits of Figs. 1 and 2 so as to secure still further benefits in accordance with a further feature of my invention.

Referring more particularly to Fig. 1, this circuit, with the exception of the portions shown in heavy lines, represents a conventional type of modulator comprising a modulator tube 1 whose grid is excited from audio source 2 and carrier source 3 via audio transformer 4 and tuned radio frequency coupling circuit 5, respectively. The audio transformer 4 is by-passed by a condenser 6 which offers negligible impedance to carrier frequencies but a high impedance to audio frequencies. The radio frequency coupling circuit 5 comprises primary coil 7 loosely coupled to secondary coil 8, the latter being tuned by variable radio frequency condenser 9. The voltages of audio transformer 4 and coupling circuit 5 are applied in series as shown between the grid and cathode of modulator tube 1, bias battery 10 being also connected in series therewith in conventional manner.

The output circuit of modulator tube 1 is also essentially conventional, comprising an output tank circuit which consists of coil 11 tuned by variable frequency condenser 12 and fed at an intermediate point with positive potential from the plate supply source 13. The neutralizing condenser 14 is connected between the grid and the end of the tank circuit remote from the anode, to provide neutralization in well known manner.

In accordance with my invention the additional apparatus shown in heavy lines is added to the conventional type of modulator above described, for the purpose of improving the effective voltage regulation of carrier source 3, thus enabling

the latter to be designed with smaller capacity and poorer regulation than in conventional systems. This additional apparatus comprises a rectifier 15 (which is preferably of the space discharge type) connected in series with a battery 16, this whole series combination being then shunted across the carrier input as shown. The voltage of battery 16 is preferably selected to be equal to the desired peak amplitude of the carrier input during conditions of maximum conductivity of the grid of tube 1. In other words, the voltage of battery 16 is preferably made equal to the amplitude of the carrier input voltage at those moments when the voltage from audio source 2 has its maximum positive value so that the grid of modulator tube 1 is drawing the greatest grid current. Such value may be computed from the known characteristics of the carrier source and the known conductivity of the modulator grid under peak voltage conditions. Alternatively this value may readily be measured by replacing transformer 4 with a direct current voltage equal to the peak audio voltage to be handled and then directly measuring the amplitude of the carrier wave across the input 8-9.

When the battery 16 is so adjusted the rectifier 15 will draw no current during peak audio intervals. During other portions of each audio cycle, however, when the grid of tube 1 is non-conductive, (or at any rate less conductive than during the peak intervals above discussed), the elimination or reduction of grid current will tend to cause the voltage across the input 8-9 to rise because of the poor regulation of source 3. As soon as such a voltage rise starts to occur the rectifier 15 will commence to draw current, thus absorbing energy from source 3. Preferably the impedance of rectifier 15 under the conditions of zero (or minimum) grid current in tube 1 should be comparatively low with respect to the rest of the circuit—e. g., less than one-sixth of the impedance of input 8-9, and preferably less than one-thirtieth thereof. Thus even a slight voltage rise will result in a relatively high dissipation of energy in this rectifier 15. Such dissipation of energy will therefore limit the voltage rise to a comparatively small value, thus reducing the distortion of a small or preferably negligible percentage.

It will be seen therefore that even with the very simple form of invention shown in Fig. 1, the voltage variations produced by the varying conductivity of the grid of output 1 are substantially compensated by varying the power absorption of the circuit branch 15, 16 in such manner that the sum of the absorptions of this circuit branch and of the grid of tube 1 is substantially constant.

It should be noted that the variations of the dissipation of the branch 15, 16 are not merely produced in synchronism with the variations of conductivity of grid 1 (as might be the case if the dissipation of this branch were controlled from the audio source 2), but rather are controlled by the grid current itself, thus being dependent upon the vary factor which is to be compensated. This is an important feature of the present invention since it insures that no matter what factors may change the grid conductivity, the compensating change in dissipation of the absorption branch 15, 16 will always automatically adjust itself to correspond with the grid dissipation of tube 1. Furthermore, the curve of variation of the dissipation of branch 15, 16

5 will accurately simulate the complex curve of variation of grid dissipation in tube 1, thus giving a more perfect compensation than could be readily obtained by a regulating arrangement which was controlled by some other factor than the grid current itself.

Fig. 2 represents another embodiment essentially similar to that of Fig. 1, except that the basic modulating circuit is of the well-known 10 shunt input type rather than of the series input type shown in Fig. 1. The difference is essentially that audio transformer 4 is connected between the grid and cathode of modulator tube 1 in shunt to the carrier input 8-9 rather than in 15 series therewith. Preferably, a radio frequency choke 17 is added in series with this audio transformer 4 so that the carrier frequency cannot back up therethrough. Since this shunt type of modulator circuit is in itself well-known, no 20 further explanation thereof is believed necessary. Because of the close similarity between this circuit and that of Fig. 1 corresponding parts are correspondingly numbered in both figures.

The operation of the absorption circuit 15, 16 25 is the same in the circuit of Fig. 2 as in that of Fig. 1, the voltage of battery 16 being preferably adjusted so that this circuit draws substantially no current during audio peaks and the impedance of rectifier 15 being preferably so low that a very 30 slight rise in radio frequency voltage causes the circuit 15, 16 to dissipate considerable energy, thus limiting such voltage rise to a negligible amount.

Figs. 3-9 represent circuit modifications which 35 may be substituted either in the circuit of Fig. 1 or that of Fig. 2, the fragmentary circuits illustrated in Figs. 3-9 being intended to directly replace those portions of Figs. 1 and 2 which are enclosed within the dot-dash lines.

40 Referring to Fig. 3, this differs from the arrangement of Figs. 1 and 2 in that battery 16 is replaced by the combination of a cathode resistor 16B and a by-pass condenser 16A. Preferably, this condenser 16A is so large as to present negligible impedance not only with respect to the carrier but also with respect to audio frequencies, so that the potential across this condenser will be substantially constant over a period covering several cycles of the lowest desired audio frequency. For convenience in understanding the invention directly from the drawing this condenser 16A has correspondingly been illustrated as having several plates in order to indicate in a rough way that its capacity is higher than that 55 of an ordinary by-pass condenser. Similarly in the other figures of drawing all condensers intended to have negligible impedance with respect to both audio and radio frequencies are represented in similar manner.

60 The modified circuit of Fig. 3 operates essentially like that of Figs. 1 and 2. It is true that this condenser resistor circuit 16A and 16B will regulate the voltage of the carrier input to a very slightly lower voltage during the transmission of modulated waves than during the transmission of unmodulated carrier. This is because during each audio peak the rectifier 15 will momentarily cease to pass current and therefore the mean current averaged over several audio cycles will 65 tend to be slightly less when modulation is present than when it is absent. The voltage of the resistor-condenser combination 16A-16B will therefore fall off. This falling off of voltage, however, will be extremely small, because the slight

est reduction of this voltage immediately cause a sharp increase of the current through rectifier 15, thus quickly checking the voltage reduction. The only effect of this will be that the carrier amplitude will rise very slightly in the absence of modulation; which is ordinarily of no consequence.

Fig. 4 represents another modification of Figs. 1 and 2 which permits the absorption circuit 15, 16 to be connected to ground, thus rendering it more convenient to excite the cathode thereof and in other ways facilitating the practical design. In the arrangement of Fig. 4 the absorption circuit 15, 16 is not galvanically connected across the secondary 8-9 of the carrier coupling arrangement but is effectively connected thereacross by connecting this absorption circuit to an extra winding 18 which is closely coupled inductively to the winding 8. The transformer thus constituted by windings 8 and 18 may, if desired, have a voltage step-up so that the impedance of rectifier 15 as viewed from coil 8 will appear to be even lower than it actually is, thus enabling a still closer voltage regulation to be obtained.

The circuit modification shown in Fig. 5 is very similar to that of Fig. 4, excepting that a triode 15A replaces the diode 15. Correspondingly, the battery 16 is connected between grid and cathode of the triode 15A rather than between anode and cathode thereof, thus permitting the use of a lower voltage battery and enabling the cathode of tube 15A to be directly grounded.

It should be clear, however, that the position of the battery in this or any other figures may be altered in many ways without essentially changing the operation of the invention. For example, battery 16 in Fig. 4 could be connected between coil 18 and the grounding point, thus permitting the direct grounding of the cathode of tube 15; or the same effect could be produced by connecting the battery 16 between anode and winding 18 in Fig. 4. Similarly, in Fig. 5 battery 16 can be connected in the grid lead as shown, in the cathode lead, in the anode lead, or in the lead between coil 18 and ground. Also in the later figures hereafter described the positions of the batteries can be similarly changed with good results. In Fig. 6, for example, battery 16 may be connected next to the cathode to bias both the grid and anode with some advantages. If desired a plurality of batteries can be used simultaneously in several such positions.

In the last four Figures 6, 7, 8 and 9, triode 15A is used as in Fig. 5 and is inductively coupled to the carrier input as in Figs. 4 and 5. These last four figures essentially differ from those previously described, however, in that each of them includes a leak-and-condenser combination 19-20 connected in series with the grid of modulator tube 1 so as to be traversed by the grid current thereof, and connections for controlling the conductivity of the triode 15A in accordance with the voltage drop developed across such leak-and-condenser combination 19-20. By such an arrangement it is possible to fully compensate for the voltage drop produced by increasing conductivity of the modulator grid or even if desired to produce overcompensation so that the carrier amplitude actually rises at the times of maximum grid current.

Referring more particularly to Fig. 6 the absorption triode 15A has its anode-cathode path tightly coupled to the carrier input circuit 8-9 by extra coil 18 as described in connection with

Figs. 4 and 5. The grid of this absorption triode 15A is biased by battery 16 preferably to such a negative value that the tube 15A will not pass any substantial current even at the radio frequency peaks, so long as the maximum grid current is flowing in the grid of modulator 1 and is thus producing a voltage drop across resistor 19 to form an additional negative bias for the grid of the absorption triode 15A. If the circuit is so adjusted, then when the grid of the modulator tube is not drawing its minimum grid current (i. e. during the valleys or intermediate portions of the audio frequency cycle), the absorption triode 15A will draw a pulse of radio frequency current at each radio frequency peak, thus absorbing power from carrier source 3.

By proper adjustment of the grid leak 19 the amount of power dissipated in triode 15A during the intervals when the main grid current through resistor 19 is zero can be made equal to, greater than, or less than the amount of power dissipated by the grid of the modulator tube 1 when the latter draws grid current at the positive peaks of an audio cycle of the greatest amplitude to be handled. Correspondingly, therefore, the circuit arrangement of Fig. 6 will act to exactly offset, over-compensate or under-compensate for the changes in carrier voltage which result from changes of grid current in the modulator tube.

It will be noted that even with a zero value of leak resistor 19 an approximate voltage regulation will be obtained especially if tube 15A has a low impedance compared to input 15A because the circuit will then resemble that of Fig. 5 and will absorb increasing amounts of power in response to any rise in radio frequency voltage which may result from the decrease of modulator tube grid current as the applied audio frequency voltage drops away from its maximum peak value. With a small value of resistor 19, not large enough to give full compensation, the circuit will therefore operate partially by the control effect of this resistor and partially according to the principles of Fig. 5. On the other hand, if resistor 19 is a little too large so as to tend to produce overcompensation, the amount of overcompensation will be very slight; because the rise in radio frequency voltage will be limited due to the increased conductivity of tube 15A which results from the increased voltage across its anode and cathode. Thus it will be seen that the value of resistor 19 is not at all critical, at least when tube 15A is of low impedance. This avoids any possible need for readjusting this resistor when tubes are changed.

In accordance with a further feature of my invention, a circuit arrangement such as shown in Fig. 6, is adjusted so as to not only compensate for the changes in carrier frequency voltage which result from varying conductivity of the modulator grid but also to considerable overcompensate for these changes so that the carrier frequency voltage applied to the modulator grid rises substantially at those times when the modulator grid draws the most grid current. For this purpose the anode cathode circuit is preferably given an impedance not less than that of the input 8-9, or at any rate not less than a third this value. By means of such overcompensation it is possible to correct any distortions introduced by the falling off of the audio frequency voltage which also occurs at times of maximum modulator grid conductivity if the audio driver 2 has imperfect regulation.

When so adjusted the circuit of Fig. 6 does not prevent the audio frequency voltage from falling off at times of maximum modulator grid conductivity, and thus does not prevent a slight flattening of the peaks of the input audio frequency voltage applied to the modulator grid. The circuit of Fig. 6 can, however, be made to compensate for the distortions in the modulated wave output of the modulator tube 1 by adjusting this circuit to produce sufficient overcompensation of the radio frequency voltages. When this is done the total effect will be that at moments of maximum grid current in the grid of the modulator tube 1 the audio frequency voltage will slightly fall off, but simultaneously and correspondingly the radio frequency voltage will rise. If these two opposite effects are properly proportioned with respect to the characteristic of the modulator tube itself, the net result can be made to be the same as if both the radio frequency and audio frequency driver had such perfect regulation that neither of these voltages were changed in any manner when the grid of the modulator tube began to draw grid current.

Fig. 7 represents a modification of Fig. 6 wherein the battery 16 is replaced by a resistor-condenser combination 16A, 16B, somewhat as in the arrangement of Fig. 3 previously described. Such modification introduces substantially no change in the manner of operation excepting that the mean carrier level of the output wave will very slightly rise, as explained in connection with Fig. 3, during extended periods of no modulation or weak modulation, such as in intervals between syllables in the case of speech or during silent periods on the program. As previously mentioned, this is of little consequence.

Fig. 8 represents a circuit modification wherein an additional amplifier tube is connected between the leak-and-condenser combination 19, 20 and the absorption triode 15A for the purpose of amplifying the voltage drop produced by such leak-and-condenser combination to provide a greater range of variation of the impedance of the triode 15A. This figure is, in many respects, similar to Fig. 7 and corresponding parts are correspondingly numbered to facilitate comparison thereof.

In the circuit of Fig. 8 an additional amplifying tube 21 is provided whose input circuit is connected across the resistor-and-condenser combination 19, 20 and whose anode cathode circuit is coupled to the grid of the absorption triode 15A by way of cathode coupling resistor 22. This cathode coupling resistor 22 also acts as a cathode self-bias for the amplifier 21. Because of the fact that this resistor must also serve as the coupling resistor for the output of tube 22, the impedance thereof is preferably more than sufficient to give suitable bias for tube 21 itself, and accordingly a battery 23 is connected in series therewith to partially nullify the drop in this resistor 22 so as to bring the grid bias of tube 21 to a desired value. This battery 23 also serves to render the grid of tube 15A negative with respect to the corresponding cathode so that in some cases the condenser-and-resistor combination 16A, 16B shown in Fig. 8 may be omitted.

It will be noted that tube 21 serves as a direct current amplifier, its input being galvanically coupled to the resistor 19 which develops the control voltage (in response to grid current through the modulator tube), and its output be-

ing galvanically coupled to the grid of absorption triode 15A. The circuit of Fig. 8 like that of Figs. 6 and 7 should preferably be adjusted so that the absorption triode absorbs substantially no power from the carrier source when the modulator grid is drawing its maximum grid current. In the case of Fig. 8 this adjustment may be made by varying either the potential of battery 23 or the value of resistor 16B. Preferably both of these are adjusted to bring the tubes 21 and 15A to convenient points on their operating curves. The amount of control exerted by Fig. 8, like that of Figs. 6 and 7, depends largely upon the value of the grid current resistor 19, and may be adjusted to produce either exact compensation of the radio frequency voltages or overcompensation thereof—in case it is desired to offset some poor regulation of the audio frequency.

Fig. 9 is very closely similar to the circuit shown in Fig. 8 except that the galvanic connections to tube 21 are replaced by capacity coupling through the large condensers 24 and 25 so that this amplifier 21 merely amplifies the changes in the drop across resistor 19, rather than the absolute value of this drop. In addition, the circuit of Fig. 9 dispenses with battery 23 by returning the grid of tube 21 to an intermediate point on resistor 22 so that the grid bias of tube 21 is determined only by the upper portion of this resistor 22, whereas the whole of resistor 22 serves as the coupling resistor for coupling this tube to the triode 15A. This return of the grid of tube 21 to an intermediate point of resistor 22 is effected through a conventional grid coupling resistor 26 with which resistor 27 and condenser 28 are associated so that these three elements form a filter. Such filter 27—28 serves to minimize degenerative coupling which might otherwise occur as a result of the common impedance constituted by the lower half of resistance 22.

The circuit of Fig. 9, like those of Figs. 6, 7 and 8, may be made to exactly compensate or overcompensate for radio frequency voltage variations, thus being capable of taking care of poor regulation not only in the carrier frequency driver 3 but also in the audio frequency driver 2, or in the latter alone if the carrier source inherently has good regulation. As in the other figures, grid current resistor 19 may be used to control the amount of compensation as to adjust the circuit for exact compensation or overcompensation in any desired degree.

It should be noted that in the various embodiments of Figs. 1-9 the adjustment of battery 16 (or of the corresponding resistor-condenser combination 16A-16B) is not critical. Although it is preferred to adjust this battery so that no unnecessary energy absorption will occur in the absorption circuit, nevertheless the arrangement will operate satisfactorily even if the battery has a somewhat lower voltage. In the latter case the only result will be that the maximum carrier amplitude will be automatically reduced to equal the voltage of battery 16, so that some unnecessary dissipation of power will take place in the absorption circuit even during the audio peaks.

For convenience, my invention has been described in connection with a modulating system of the type wherein low frequency modulating signals are employed to modulate a high frequency carrier, thus producing a modulated output wave consisting of a carrier and two side-

bands. The invention is applicable, however, to all kinds of modulating systems such as those delivering suppressed carrier and/or single sideband modulated waves. The invention is also applicable to the so-called heterodyne demodulators or frequency changers wherein a high frequency signaling wave consisting of one or two side bands is used to modulate the carrier so as to yield a modulated wave which may be of low frequency corresponding to the difference between the carrier and signal waves or of high frequency corresponding to their sum.

In Fig. 1 for example, audio source 2 may be replaced by a source of high frequency single or double sideband signals, the audio transformer 4 being correspondingly replaced by a high frequency transformer, and the carrier by-pass condenser 6 being omitted or replaced by a series resonant circuit of high impedance elements tuned to the frequency of source 3 so as to bypass the carrier only. In Fig. 2 similar alteration may be made in this figure it may also be desirable to omit carrier blocking choke 17 or to replace it by a shunt resonant circuit of low impedance elements tuned to block the carrier only. The modification shown in Figs. 3-9 will still be suitable for application to such altered systems using high frequency signal inputs, the condensers 16A, 24, and 25 being then made large, not only with respect to the high frequency signal waves but also with respect to the frequency of the modulated output waves if these are of lower frequency than the input waves. Such modified modulation systems may be of the so-called "demodulation" or "frequency changing" type, the output wave being either higher or lower than the input signal wave. In fact the frequency range of the output wave may even overlap the frequency range of the input wave if the modulator is balanced in known manner to suppress the input signal in the output circuit.

Since all such systems are really modulating systems whether they be called modulators, demodulators or frequency changers, the expressions "modulating system," "modulating source," "modulating voltage," etc., are used generically in the appended claims without regard to whether the input signal wave is of low frequency and the output wave of high frequency or vice versa.

What I claim is:

1. A modulation system which comprises a discharge tube having a cathode, an anode and a grid, means for normally biasing said grid to draw substantially no grid current, a carrier source connected to apply an unmodulated carrier voltage between said grid and cathode, a modulating source connected to apply a further modulating voltage between said grid and cathode, the voltages of said sources being sufficient to cause the flow of substantial grid current, at least during overlapping peaks of said carrier and modulating voltages and the voltage of at least one of said sources being subject to substantial variation with varying load, absorption means for normally absorbing power from said carrier source, and means responsive to the flow of grid current for decreasing the absolute power absorbed by said absorption means.

2. A modulation system which comprises a discharge tube having a cathode, an anode and a grid, means for normally biasing said grid to draw substantially no grid current, a carrier source whose voltage is subject to substantial variations with varying load, connected to apply

- an unmodulated carrier voltage between said grid and cathode, a modulating source connected to apply a further modulating voltage between said grid and cathode, the voltages of said sources being sufficient to cause the flow of substantial grid current at least during overlapping peaks of said carrier and modulating voltages, absorption means for normally absorbing power from said carrier source, and means responsive to the flow of grid current for decreasing the absolute power absorbed by said absorption means.
3. A system according to claim 2 wherein said power absorption means comprises a circuit incorporating rectifier means and wherein said means responsive to the flow of grid current for decreasing the absolute power absorbed by said absorption means comprises means associated with said rectifier means for causing the impedance thereof to increase sharply in response to small decreases in said carrier voltage, whereby the carrier voltage reduction which inherently results from any substantial increase in grid current causes a substantial decrease in the power absorption of said absorption means.
4. A system according to claim 2 wherein said means responsive to the flow of grid current for decreasing the absolute power absorbed by said absorption means comprises means associated with said absorption means for causing the power absorption thereof to decrease sharply in response to small decreases in said carrier voltage, whereby the carrier voltage reduction which inherently results from any substantial increase in grid current causes a substantial decrease in the power absorption of said absorption means.
5. A modulation system which comprises a discharge tube having a cathode, an anode and a grid, means for normally biasing said grid to draw substantially no grid current, a carrier source connected to apply a carrier voltage between said grid and cathode, a modulating source connected to apply a further modulating voltage between said grid and cathode, the voltages of said sources being sufficient to cause the flow of substantial grid current at least during overlapping peaks of said carrier and modulating voltages, and the voltage of at least one of said sources being subject to substantial variations with varying load, absorption means for normally absorbing power from said carrier source, means for deriving from said grid current a voltage dependent on the value of said grid current, and means for controlling the impedance of said absorption means from said derived voltage.
6. A system according to claim 5 wherein the voltage of at least said modulating source is subject to substantial variations with varying load and wherein said means for deriving a voltage from said grid current and said means for controlling the impedance of said absorption means from said derived voltage comprise an impedance connected to be traversed by said grid current and proportioned to cause a rise in said carrier voltage in response to increasing grid current.
7. A system according to claim 2 wherein said means for decreasing said power absorption responsive to increasing grid current comprises means associated with said absorption means for causing the power absorption thereof to decrease sharply in response to small decreases in said carrier voltage, whereby the carrier voltage reduction which inherently results from any substantial increase in grid current causes a substantial decrease in the power absorption of said absorption means and further comprises means

for deriving from said grid current a voltage dependent on the value of said grid current, and means for controlling the impedance of said absorption means from said derived voltage.

8. A modulation system which comprises a modulating discharge tube having a cathode, an anode and a grid, means for normally biasing said grid to draw substantially no grid current, source of unmodulated carrier waves whose voltage is subject to substantial variation with varying load connected to apply a carrier voltage between said grid and cathode, a modulating source connected to apply a separate modulating signal voltage between said grid and cathode, the voltages of said sources being sufficient to cause the flow of substantial grid current, at least during overlapping peaks of said carrier and modulating signal voltages, an output circuit for deriving from said anode a modulated signal voltage resulting from the modulation of said carrier voltage by said modulating signal voltage, a further discharge tube having a control electrode and a space path whose impedance is controlled thereby, an absorption circuit including said space path and connected to normally absorb power from said carrier source, and means for increasing the impedance of said space path sharply responsive to small absolute decreases in said carrier voltage.

9. A system according to claim 8, wherein at least one of said signal voltages is of substantially lower frequency than said carrier voltage, further comprising means for deriving from said grid current a voltage dependent on the mean value of said grid current averaged over a number of carrier cycles but over only a portion of a cycle of said lower frequency signal voltage, and means for applying said derived voltage to said control electrode to further vary the impedance of said space path.

10. A system according to claim 8, wherein said modulating signal voltage is of substantially lower frequency than said carrier voltage, further comprising means for deriving from said grid current a voltage dependent on the mean value of said grid current averaged over a number of carrier cycles but over only a portion of a cycle of said modulating signal voltage, and means for applying said derived voltage to said control electrode to further vary the impedance of said space path.

11. A modulation system which comprises a modulating discharge tube having a cathode, an anode and a grid, means for normally biasing said grid to draw substantially no grid current, a carrier source connected to apply a carrier voltage between said grid and cathode, a modulating source connected to apply a modulating signal voltage between said grid and cathode, the voltages of said sources being sufficient to cause the flow of substantial grid current at least during overlapping peaks of said carrier and modulating signal voltages and the voltage of at least one of said sources being subject to substantial variations with varying load, an output circuit for deriving from said anode a modulated signal voltage resulting from the modulation of said carrier voltage by said modulating signal voltage, at least one of said signal voltages being of substantially lower frequency than said carrier voltage, a further discharge tube having a control electrode and a space path whose impedance is controlled thereby, an absorption circuit including said space path and connected to normally absorb power from said carrier source, means for

deriving from said grid current a control voltage dependent on the value of said grid current said means including a resistor and condenser having a time constant corresponding to a number of carrier cycles but to only a small part of a cycle of said lower frequency signal voltage, and means for applying said control voltage to said control electrode to vary the impedance of said space path.

10 12. A modulation system which comprises a modulating discharge tube having a cathode, an anode and a grid, means for normally biasing said grid to draw substantially no grid current, a carrier source connected to apply a carrier voltage between said grid and cathode, a modulating source connected to apply a modulating voltage of substantially lower frequency than said carrier voltage between said grid and cathode, the voltages of said sources being sufficient to cause the flow of substantial grid current at least during overlapping peaks of said carrier and modulating voltages and the voltage of at least one of said sources being subject to substantial variations with varying load, a further discharge tube having a control electrode and a space path whose impedance is controlled thereby, an absorption circuit including said space path and connected to normally absorb power from said carrier source, means for deriving from said grid current a control voltage dependent on the value of said grid current said means including a resistor and condenser having a time constant corresponding to a number of carrier cycles but to only a small part of a cycle of said modulating voltage, and means for applying said control voltage to said control electrode to vary the impedance of said space path.

13. A modulation system which comprises a modulating discharge tube having a cathode, an anode and a grid, means for normally biasing said grid to draw substantially no grid current, a carrier source connected to apply a carrier voltage between said grid and cathode, a modulating source connected to apply a modulating signal voltage between said grid and cathode to produce by modulation a modulated signal voltage, at least one of said signal voltages being of substantially lower frequency than said carrier voltage, the voltages of said sources being sufficient to cause the flow of substantial grid current at least during overlapping peaks of said carrier and modulating signal voltages and the voltage of at least one of said sources being subject to substantial variations with varying load, a further discharge tube having a control electrode and a space path whose impedance is controlled thereby, an absorption circuit including said space path and connected to normally absorb power from said carrier source, means for deriving from said grid current a unidirectional control voltage dependent on the value of said grid current said means including a resistor and condenser having a time constant corresponding to a number of carrier cycles but to only a small part of a cycle of said lower frequency signal voltage, and means for applying said unidirectional control voltage to said control electrode to vary the impedance of said space path.

14. A modulation system which comprises a modulating discharge tube having a cathode, an anode and a grid, means for normally biasing said grid to draw substantially no grid current, a carrier source connected to apply a carrier voltage between said grid and cathode, a modulating source connected to apply a modulating voltage

of substantially lower frequency than said carrier voltage between said grid and cathode, the voltages of said source being sufficient to cause the flow of substantial grid current at least during overlapping peaks of said carrier and modulating voltages and the voltage of at least one of said sources being subject to substantial variations with varying load, a further discharge tube having a control electrode and a space path whose impedance is controlled thereby, an absorption circuit including said space path and connected to normally absorb power from said carrier source, means for deriving from said grid current a unidirectional control voltage dependent on the value of said grid current said means including a resistor and condenser having a time constant corresponding to a number of carrier cycles but to only a small part of a cycle of said modulating voltage, and means for applying said unidirectional control voltage to said control electrode to vary the impedance of said space path.

15. A modulation system which comprises a first discharge tube having a cathode, an anode and a grid, means for normally biasing said grid to draw substantially to grid current, a carrier source connected to apply a carrier voltage between said grid and cathode, a modulating source connected to apply a modulating signal voltage between said grid and cathode to produce by modulating a modulated signal voltage, at least one of said signal voltages being of substantially lower frequency than said carrier voltage, the voltages of said sources being sufficient to cause the flow of substantial grid current at least during overlapping peaks of said carrier and modulating signal voltages and the voltage of at least one of said sources being subject to substantial variations with varying load, a further discharge tube having a control electrode and a space path whose impedance is controlled thereby, an absorption circuit including said space path and connected to normally absorb power from said carrier source, means for deriving from said grid current an alternating control voltage dependent on the value of said grid current said means including a resistor and condenser having a time constant corresponding to a number of carrier cycles but to only a small part of a cycle of said lower frequency signal voltage, and means for applying said alternating control voltage to said control electrode to vary the impedance of said space path.

16. A modulation system which comprises a first discharge tube having a cathode, an anode and a grid, means for normally biasing said grid

to draw substantially no grid current, a carrier source connected to apply a carrier voltage between said grid and cathode, a modulating source connected to apply a modulating voltage of substantially lower frequency than said carrier voltage between said grid and cathode, the voltages of said sources being sufficient to cause the flow of substantial grid current at least during overlapping peaks of said carrier and modulating voltages and the voltage of at least one of said sources being subject to substantial variations with varying load, a further discharge tube having a control electrode and a space path whose impedance is controlled thereby, an absorption circuit including said space path and connected to normally absorb power from said carrier source, means for deriving from said grid current an alternating control voltage dependent on the value of said grid current said means including a resistor and condenser having a time constant corresponding to a number of carrier cycles but to only a small part of a cycle of said modulating voltage, and means for applying said alternating control voltage to said control electrode to vary the impedance of said space path.

17. A system according to claim 11 wherein the voltages of both said sources are subject to substantial variations with varying loads on the sources, and wherein said resistor comprised in said means for deriving a control voltage from said grid current is proportioned to derive a voltage sufficient to more than compensate for said variations in the voltage of the carrier source, so as to at least partially compensate also for said variations in the voltage of said modulating source.

18. A system according to claim 13 wherein said resistor is connected to be traversed by said grid current to produce a unidirectional potential drop and wherein said means for deriving a unidirectional voltage from said grid current further comprises direct current amplifying means for amplifying said unidirectional potential drop to yield said unidirectional control voltage.

19. A system according to claim 15 wherein said means for deriving an alternating control voltage from said grid current includes an impedance traversed by said grid current to produce a unidirectional potential drop and alternating current amplifying means for amplifying the fluctuations of said unidirectional potential drop to yield said alternating control voltage.

FREDERICK E. TERMAN.
